UNITED STATES PATENT OFFICE

2,193,619

REEL FOR AIRCRAFT ANTENNAS AND THE
LIKEWilliam K. Clements, Brunswick, N. Y., assignor
to General Electric Company, a corporation of
New YorkApplication May 14, 1937, Serial No. 142,637
Renewed September 20, 1939

6 Claims. (Cl. 242—99)

My invention relates to reels, especially to reels for use in connection with aircraft antennas. The invention is particularly directed to aircraft antenna reels or like reels wherein by movement of a handle or other actuating element in one direction of rotation the antenna may be reeled in, and by movement of the same actuating element in the opposite direction through a relatively few degrees of rotation, the antenna may be unreeled and the unreeling operation may be controlled by means of a braking mechanism.

It has been proposed heretofore, for the purpose of unwinding and suspending an aircraft antenna wire from the craft after it leaves the ground and of thereafter returning the antenna to the craft before it descends, to provide an antenna reel which is turned in both the reeling or winding and the unreeling or unwinding direction by a handle in the manner of a conventional windlass.

It has also been proposed, in order to expedite the unwinding of the antenna as the craft ascends, to provide the antenna reel, having a handle for the winding in of the antenna, with a separate brake, clutch, or latch mechanism whereby the antenna could be unwound rapidly from the reel by its own weight, assisted by the usual weight fastened at the end thereof, without the necessity of the relatively slow manual unwinding by means of the handle. The addition of the brake, clutch, or latch mechanism to the simple handle-operated reel has, however, been open to the objection that the operator was required to employ both hands to control the reel device.

To overcome the above objection to the last-named antenna reel devices, it has further been suggested heretofore to provide an aircraft antenna reel device characterized by having only a single handle or other actuating element for reeling in the antenna and for controlling the unreeling operation. Difficulties have been encountered, however, in the attempt to provide reeling devices of this latter type, by reason of the space and weight limitations and the severe constructional and operational requirements imposed upon reel devices of this character for use in aircraft and particularly in airplanes.

It is the general object of my present invention to provide an antenna reel for aircraft use, and particularly for airplane use, which overcomes the above and other difficulties encountered in prior antenna reel devices.

A particular object is to provide an improved

antenna reel of the type wherein a single handle or other single actuating means is utilized both for the winding in of the antenna and for the control of the unreeling thereof.

In accordance with my invention, the above-mentioned and other difficulties are avoided and the above and other objects are attained by the provision of a compact antenna reeling device which is at the same time of simple and rugged construction, incorporating a clutch and brake mechanism of the multiple disk type.

The novel features which I believe to be characteristic of my invention are set forth with particularity in the appended claims. My invention itself, however, both as to its organization and operation together with further objects and advantages thereof may best be understood by reference to the following description taken in connection with the accompanying drawing.

Referring to the drawing, Fig. 1 is a side-elevational view, partially in section, of an antenna reel device in accordance with my invention; Fig. 2 is a front elevational view of the device illustrated in Fig. 1; Fig. 3 is an enlarged cross-sectional view, partially broken away, on line A—A of Fig. 1; Fig. 4 is a side-elevational view of a portion of the device illustrated in Figs. 1 and 2, the view in Fig. 4 being partially in section on line B—B of Fig. 3 and also showing the multiple disk brake or clutch elements in the antenna winding-in or reeling position; Fig. 5 is similar to Fig. 4 but shows the brake elements in the antenna unwinding or unreeling position; and Figs. 6, 7 and 8 are sectional views illustrating the construction of a folding handle for manually operating the reel device.

In Fig. 1, the numeral 1 indicates a base member which may be fastened in any suitable manner in an aircraft, for example at a point in an airplane adjacent the pilot's position. A shaft 2 is fastened to base 1 and a brake support member or sleeve 3 is rotatably mounted on shaft 2. A means is provided, preferably comprising ratchet teeth 4 formed on the end of brake sleeve 3 and a plurality of pawls, as pawl 5, pivoted on pin 6 secured to base 1, to prevent rotation of sleeve 3 except in the winding-in or reeling direction. The numeral 7 indicates a reel hub member surrounding brake sleeve 3 and mounted to be rotated with reference to this sleeve during the unwinding or unreeling operation, and to be locked to the sleeve during the winding operation. To cause the hub member 7 to be rotated with sleeve 3 for reeling in the antenna, and to cause the hub member to free-wheel or

run free of sleeve 3 for unreeling or unwinding the antenna, a brake screw member 8 is provided at the other end of the hub member. To rotate the brake screw 8 a suitable actuating means is provided, such as a crank 9 to which is attached a handle 10 preferably foldable on a joint member 11 when not in use. The numeral 12 indicates an antenna spool of insulating material which is fastened to a flange 13 on the reel hub member 7 and which almost entirely surrounds the hub member and the mechanism enclosed thereby. A spool cover member 14 of insulating material is preferably provided which may have a plate portion 15 loosely abutting base 1 to permit the cover to adjust itself circumferentially to different positions of the antenna wire as it enters the spool 12. Preferably a revolution counter means is provided comprising a worm gear 16 which may be integral with the end of hub 7 and a driven gear 17 mounted on a shaft 18 which drives a counter dial device 19 (shown in Fig. 2).

Referring now to Fig. 4 taken in connection with Fig. 3, at a portion of brake sleeve 3 toward 25 or adjacent to that end of shaft 2 which is secured in base 1, a plurality or set of brake disks 20 are loosely keyed to the sleeve, to be rotated therewith but to be free to slide axially thereof, by providing, for example, as better shown in Fig. 3, flats 21 on the sleeve throughout this portion thereof and by punching corresponding flats 22 on the disks. At the portion of hub member 7 surrounding the above-mentioned portion of brake sleeve 3, a second plurality or set of brake 30 disks 23 are provided interleaved with the first set and loosely keyed to the hub member for rotation of the hub member with the latter disks while permitting the disks to slide freely axially of the member, as by providing, as shown more 35 clearly in Fig. 3, notches or recesses 24 in the hub member and by punching corresponding lugs 40 25 on the disks.

The brake screw 8 has a flange portion 26, and a ring or sleeve portion 27 rotatably mounted on 45 brake sleeve 3 adjacent to the outer end of this sleeve. A retaining nut 28 is screwed to the outer end of brake sleeve 3, and an antifriction bearing 29 is preferably provided between the retaining 50 nut and the brake screw 8. The hub member 7 is rotatably mounted with reference to the brake sleeve 3 by means, preferably, of antifriction bearings 30 and 31 at the opposite ends of the hub member and running on bearing races provided, respectively, on the flange portion 26 of the brake 55 screw 8 and on that end of the bearing sleeve 3 which is adjacent to the base plate 1.

To enable the operator, as desired, either to cause pressure to be applied to the sets of disks 20 and 23 or to release the pressure on the disks 60 partially or completely, steep pitched screw threads 32 are formed on the sleeve portion 27 of brake screw 8 and corresponding screw threads 33, cooperating with threads 32, are formed at one end of a brake nut member or sleeve 34 which is 65 splined at its other end to the brake sleeve 3; a relatively heavy helical compression spring 35 is mounted between a flange 36 of brake nut 34 and a thrust member or washer 37 between which and brake screw 8 is interposed a preferably anti-friction bearing 38; a spacer member or ring 39 is 70 preferably provided, splined to the brake sleeve 3, between the sets of brake disks 20 and 23 and the end of brake nut 34 opposite the threaded end thereof; and a second or auxiliary helical compression spring 40, lighter than or under less 75

compression than spring 35, is mounted between brake nut 34 and spacer ring 39. In order to make the device still more compact the smaller spring 40 is telescoped within the larger spring 35, thus being located in the space between the latter spring and brake sleeve 3, for example preferably in a recess 41 formed in the end of brake nut 34.

In Fig. 5 the various elements are the same in construction as in Fig. 4, but in Fig. 5 the brake 10 and brake control elements of the reel device are shown in position to permit the spool hub member 7 to rotate freely for the paying out or unreeling of the antenna, whereas in Fig. 4 the 15 brake and brake control elements are shown for the locked or the braking condition of spool hub member 7.

Referring to Figs. 6 to 8, and more particularly to Fig. 6, the assembly of the foldable handle 10 and crank 9 comprises a handle outer shell 42 and an inner sleeve 43 inserted therein internally threaded at its outer extremity to receive a bushing 44, having a head portion 45, through which bushing passes a plunger rod 46 having a push-button 47 on its outer extremity and a plunger 48 on its inner extremity, a light spring 49 being mounted within the sleeve 43 and between the bushing 44 and the plunger 48 to bias the plunger inwardly of the handle. The handle 10 is attached to the crank 9 by means of a ring or sleeve 30 49' which is preferably formed integrally with handle inner sleeve 43 and which is rotatably mounted on a cylindrical end portion 50 of the crank, being retained thereon by a plate 51 secured thereto by a screw 52. A handle lock member or 35 plunger 53 is mounted within a recess 54 formed within the cylindrical portion 50 at right angles to the axis thereof, the recess being open at one end and closed at the other, and so spaced from the end of the crank that as the handle 10 is 40 swung about the crank end 50 the recess may come into alignment with the opening 55 through handle sleeve 43. In order to cause locking of the handle 10 in operating position, a spring 56 is so mounted in the recess 54 as to bias the lock 45 or plunger 53 in the direction of the open end of the recess.

In operation of the antenna reel device in accordance with my invention, when the manual or other actuating means, in the present instance 50 handle 10, is in normal or released condition, the brake and control elements assume the positions illustrated in Fig. 4, wherein the pressure of the heavy or main spring 35, exerted at the left-hand end thereof against retaining nut 28 of brake 55 sleeve 3 through thrust ring 37, bearing 38, brake screw 8 and bearing 29, and at the right-hand end against the brake disks 20 and 23 through brake nut 34 and spacer ring 39, causes the set of disks 23 to be locked to the set of disks 20 thereby locking the antenna spool hub member 7 to the brake sleeve 3. In this position of the reel elements the antenna wire cannot run out since rotation of brake sleeve 3 in the unreeling direction, which is counter-clockwise looking from the crank end 65 of the device, is prevented by the pawl and ratchet means 4 and 5. However, the spool hub member 7, thus locked to brake sleeve 3, may be rotated in the clockwise or antenna winding-in or reeling direction by clockwise rotation of the crank 9, 70 operating through brake screw 8, the screw connection of the brake screw 8 to brake nut 34, and the splined connection of brake nut 34 to brake sleeve 3, it being understood that the brake screw 8 and brake nut 34 are so threaded, having left- 75

hand threads in the present instance, that clockwise rotation of the crank 9 for reeling in the antenna tends to drive the brake sleeve disks 20 into still tighter engagement with spool hub member disks 23.

When it is desired to pay out the antenna, the brake screw 8 is rotated counter-clockwise by its actuating means, crank 9. The brake nut 34 tends to be rotated with brake screw 8 but cannot do so because of its splined connection with brake sleeve 3, which itself is prevented from rotating counter-clockwise by the ratchet and pawls 4 and 5. Brake nut 34 is therefore moved to the left and compresses the main spring 35, as illustrated for example in Fig. 5, by reason of the screw connection, 32 and 33, of the brake nut 34 with the brake screw 3. The locking pressure on disks 23 and 20 is thus reduced, the reel being permitted to rotate under influence of the weight of the antenna and being braked by pressure applied between disks 23 and 20 by reason of spring 40. Upon further rotation of the handle the brake nut 34 is moved further to the left thus reducing the pressure exerted by spring 40 and therefore the braking effort, until finally the pressure is completely removed and the reel free wheels rapidly to pay out the antenna.

If the antenna pays out too rapidly the operator merely reduces some of the pressure applied to the handle, thus again causing the tension of spring 40 and finally of spring 35 to be applied to the brake disks. Thus, by proper regulation of the pressure applied to the handle in the paying out direction the rate of paying out may be regulated nicely by the operator.

If pressure on the handle be completely released, the brake disks stop the rotation of the reel. Rotating the handle in the opposite direction now causes the antenna to be reeled in. Upon initial rotation of the handle in the opposite direction, the brake nut 34 approaches the spacer ring 39, but the auxiliary compression spring 40, which in its extended condition as shown in Fig. 5 projects beyond the right-hand end of brake nut 34, comes into engagement with the spacer ring 39 in advance of the brake nut 34, thereby causing an initially relatively light but progressively greater pressure from spring 40 to be exerted on disks 20 and 23, followed by the full pressure of main spring 35 as brake nut 34 finally makes engagement with spacer ring 39.

During the rotation of brake screw 8 with respect to brake nut 34, for the purpose as above described of locking or of unlocking the clutch disks 20 and 23, the interposing of the thrust means comprising thrust ring 37 and antifriction bearing 38, between the heavy main spring 35 and the brake screw 8, effectually prevents twisting or cramping of this heavy main spring which would otherwise occur with resulting interference with the desired effective braking and holding power of the brake assembly.

It will be understood that the pitch of the screw threads 32 and 33 is such that when the handle 10 is released by the operator after rotation of the crank 9 in the counter-clockwise direction to permit free wheeling of the spool hub member 1, the handle is immediately returned to its normal non-operating fixed position by the pressure of spring 35. This pitch is, however, such that easy operation of the brake means by counter-clockwise rotation of the handle is assured.

Referring to the operation of the foldable handle means, in Figs. 6 and 7 the handle 10 is shown as held securely in operating position,

with the opening 55 of the handle in line with the recess 54 of cylindrical portion 50 of crank 9, and with the handle lock or plunger 53 projecting within the opening 55. When it is desired to fold the handle back toward the reel assembly either to the right or left, the pushbutton 47 is pressed, thereby causing the plunger 48, fixed to plunger rod 46, to drive handle lock or plunger 53 entirely within its recess 54 against the pressure of spring 56, the sleeve or ring 49' of the handle 10 holding the plunger 53 in its closed position, illustrated in Fig. 8, as the handle is then folded back. A simple and dependable handle lock arrangement is thus provided having no external springs or other operating parts, the required extra parts all being contained compactly within the handle and crank assembly.

From the foregoing description of the operation of an antenna reel in accordance with my present invention, it will be readily seen that through the interaction of the brake sleeve 3, the ratchet and pawls 4 and 5, the brake screw members 8 and 34, the main spring 35, the thrust ring 37 and its bearing 38, the auxiliary spring 40, the spacer ring 39, the multiple disk brake elements 20 and 23, and the spool hub member 1, a compact, rugged and finely controlled holding, braking, and releasing action is assured for the antenna spool 12, with automatic compensation for wear, and without roughness of movement or the danger of sudden stoppage of the spool hub member, tending to break the antenna wire, when the wire is run out to its desired length as indicated by the counter 19.

The antenna reel in accordance with the invention has been described herein as manually operated and in connection with airplane antennas. The device is, however, adaptable to motor drive, as by remote control, and further, is capable of other than antenna uses.

My invention has been described herein in a particular embodiment for purposes of illustration. It is to be understood, however, that the invention is susceptible of various changes and modifications and that by the appended claims I intend to cover any such modifications as fall within the true spirit and scope of my invention.

What I claim as new and desire to secure by Letters Patent of the United States, is:

1. In a reel, the combination with a rotatable brake support member, means to prevent rotation of said member except in the reeling direction, and a reel hub member mounted for rotation in either direction, of two sets of interleaved disks keyed respectively to said brake support member and said hub member, a brake screw member rotatably mounted with respect to said brake support member, a brake nut member threaded to said brake screw member, a resilient means, and means including said resilient means and said brake nut member to press said disks together to cause said hub member to rotate with said brake support member when said brake screw member is rotated in the reeling direction.

2. In a reel, the combination with a rotatable brake support member, means to prevent rotation of said member except in the reeling direction, and a reel hub member mounted for rotation in either direction, of two sets of interleaved disks secured respectively for rotation with said brake support member and said hub member, a brake screw member rotatably mounted on said brake support member, a brake nut member threaded to said brake screw member, resilient means interposed between said brake screw member and

said brake nut member for pressing said sets of disks together to cause said hub member to rotate with said brake support member when said brake screw member is rotated in the reeling direction, and a second resilient means interposed between said brake nut member and said disks to oppose partially the pressure of said first resilient means.

3. In a reel, the combination with a rotatable brake support member, means to prevent rotation of said member except in the reeling direction, and a reel hub member mounted for rotation in either direction, of two sets of interleaved disks secured respectively to said brake support member and said hub member, a brake screw member rotatably mounted on said brake support member and having a flange portion, a brake nut member threaded to said brake screw member, a thrust member, bearing means between said thrust member and said flanged portion of said brake screw member, and a spring interposed between said thrust member and said brake nut member for pressing said sets of disks together to cause said hub member to rotate with said brake support member when said brake screw member is rotated in the reeling direction.

4. In a reel, in combination, a supporting shaft, a rotatable brake sleeve mounted thereon, means at one end of said sleeve for preventing rotation thereof except in the reeling direction, a brake screw rotatably mounted on said sleeve adjacent to the other end thereof and having a flange portion, means operatively associated with said brake screw to move said screw in either direction of rotation, a hub member rotatably mounted between said one end of said sleeve and said flanged portion of said brake screw, a spool mounted on and surrounding said hub member, a brake nut threaded on said brake screw, two sets of interleaved disks keyed respectively to said sleeve and said hub member and mounted within the portion of said hub member adjacent to said one end of said sleeve, and spring means enclosed by said hub member in the portion thereof between said first-named portion and the other end of said sleeve for pressing said disks together when said brake screw is rotated in the reeling direction.

5. In a reel, in combination, a rotatable brake support member, means to prevent rotation of said member except in the reeling direction, a plurality of brake disks mounted on said member to rotate therewith and to slide axially thereof, a brake screw rotatably mounted on said member and having a flange portion, a hub member rotatably mounted between said brake support member and said brake screw flange portion, a plurality of brake disks interleaved with said first-named disks and mounted on said hub member to rotate therewith and to slide axially thereof, a brake nut threaded on said brake screw and mounted on said brake support member to rotate therewith and to slide axially thereof, a spacer member mounted on said brake support member between said brake nut and said disks to rotate with said brake support member and to slide axially thereof, a thrust member, bearing means between said thrust member and said brake screw, a spring mounted between said thrust member and said brake nut to cause said brake nut to press said first-named and second-named disks together through said spacer member when said brake screw is released, and a spring exerting less pressure than said first-named spring mounted between said brake nut and said spacer member.

6. The combination in a reel device having a spool member, an actuating element adapted when rotated in one direction to cause reeling operation of said spool member and in the other direction to cause unreeling operation of said spool member, and a clutch means interposed between said actuating element and said spool member, of a main spring, an auxiliary spring, and means operatively associated with said actuating element to cause when said actuating element is rotated in said one direction said main spring to exert locking pressure in said clutch means and to cause when said actuating element is rotated in said one direction said auxiliary spring to exert a preliminary locking pressure in said clutch means in advance of said locking pressure exerted by said main spring.

WILLIAM K. CLEMENTS.
